UNITED STATES PATENT OFFICE

115,962

DESIGN FOR A VANITY CASE OR SIMILAR ARTICLE

Richard T. Gaige, New York, N. Y., assignor to Volupte, Inc., Elizabeth, N. J.

Application June 26, 1939, Serial No. 85,704

Term of patent 3½ years

To all whom it may concern:

Be it known that I, Richard T. Gaige, a citizen of the United States, residing at New York city, in the county and State of New York, have invented a new, original, and ornamental Design for a Vanity Case or Similar Article, of which the following is a specification, reference being had to the accompanying drawing, forming part thereof.

Fig. 1 is a plan view of a vanity case or similar article, showing my new design.

Fig. 2 is a front view thereof.

The side of the vanity case not shown is substantially like the side shown in the drawing.

I claim:

The ornamental design for a vanity case or similar article, substantially as shown and described.

RICHARD T. GAIGE.
